UNITED STATES PATENT OFFICE

OLOF LUNDBERG, OF SALTSJOBADEN, SWEDEN

WATER CLOSET

Application filed March 26, 1931, Serial No. 525,554, and in Sweden April 2, 1930.

This invention relates to improvements in water closets having a seat lid, wherein the flushing is effected in such a manner that when the seat lid is raised a flushing cistern chamber connected to the closet is filled with the required quantity of flushing water which when the seat lid is turned down streams from the flushing cistern chamber into the closet bowl.

According to the invention the seat lid is not rigidly connected to any of the members necessary to effect the flushing, but movable freely about one or more hinges, and first in a turned-down position adapted to actuate by its weight the members effecting the flushing.

As an example, a water closet according to this invention is shown in the accompanying drawings, wherein.

Figure 1 is a vertical section of the rear part of the closet with the flushing cistern chamber and the flushing device.

Figure 2 shows on a larger scale a detail in vertical section.

Figure 3 is a vertical section on the line A—A of Figure 2, and Figure 4 is a horizontal section on the line B—B of Figure 2.

In the upper, rear part of the closet 1 there is a chamber 2, the flushing cistern chamber. That wall of the flushing cistern chamber, which is turned towards the closet bowl, is provided with a discharge-hole 3, and adjacent to said hole there is a clack valve 4. In the closet there is a vertical channel 5 formed of china and open at both ends, and a vertical pipe 6 is secured watertight to the bottom of the flushing cistern chamber, the lower end of said pipe being situated beneath the bottom of the flushing cistern chamber 2 and the closet 1. The pipe 6 forms an open channel which upwards opens above the water-level in the flushing cistern chamber when the latter has been filled with the required quantity of water.

The seat of the closet comprises three main parts, viz. the stationary seat member 6^x which is attached to the closet, the seat 7 which is screwed to the seat member 6^x by means of common hinges, and the seat lid 8 which is screwed to the stationary seat member 6^x above the seat by means of a special hinge. The latter, which is shown on a larger scale in Figures 2-4, consists of a stationary hinge member 9 attached to the stationary seat member 6^x, a movable hinge

member 10 to which the seat lid 8 is screwed, and a hinge shaft 11. The stationary hinge member 9 is provided with a recess 12, Figure 3, for an angle-lever 13 pivoted about the hinge shaft 11. When the seat lid has been turned down a projection 14 of the angle-lever 13 rests on the edge of said lid, so that the lever is held in a raised position.

In the lever 13 there is mounted a pivot 15 to which one end of the rod 16 is secured. The rod 16 extends downwards through the channel 5, and its lower end is threaded into a link 17 which by a pivot 19 slidable in a slot 18 is connected to the lever 20, one end of which is pivoted to the closet, by means of a bolt 21. The other end of the lever 20 is by a pivot 23 slidable in a slot 22 pivoted to one end of a rod 24 which extends upwards through the pipe 6, and which at its other end is connected to a guiding pipe 25 enclosing the pipe 6, and also to a supporting arm 26, to one end of which a loop-screw 27 is secured adapted to be adjusted vertically. A chain 28 connects the loop-screw 27 to the clack valve 4. The other end of the arm 26 supports the lever 30 of a float cock when the lever 20 has been raised, the float 29 being attached to said lever 30 in such a manner that it may be vertically adjusted.

The flushing device operates in the following manner:

In the initial position the turned-down seat lid 8 rests on the projection 14 of the angle-lever 13. The lever 13 and the lever 20 connected thereto by means of the rod 16, are held in a raised position by the weight of the seat lid. In this raised position of the lever the supporting arm 26 connected to said lever occupies such a position that the clack valve 4 through the chain 28 is held raised and the lever 30 of the float cock is supported by the arm 26, so that the float cock is held closed.

By threading the rod 16 more or less into the link 17 and by raising or lowering the loop-screw this initial position and the required raising height of the clack valve 4 are easily adjusted.

When the closet is to be used the seat lid 8 is raised. The lever 13 is then liberated, and the lever 20 connected thereto is swung downwards owing to the weight of the lever and that of the members operating the same until the bottom of the pipe 25 rests on the

pipe 6. The chain 28 is then slack, and the clack valve 4 closes the discharge-hole 3 of the flushing cistern chamber. The lever 30 of the float cock is now no more supported by the arm 26, and therefore the float secured to the lever 30 opens the cock owing to its weight. The water now streams to the flushing cister chamber until the water level therein has raised to such a height that the float has risen and the lever 30 has closed the cock.

When the closet has been used the seat lid 8 is turned down. When the lid has been turned down it actuates the angle-lever 13 by its weight, so that said lever is swung upwards causing the rod 16, the lever 20, the rod 24 and the arm 26 connected thereto to be raised. The clack valve is now raised by the chain 28, so that the flushing water collected in the flushing cistern chamber streams through the discharge-hole 3 into the closet bowl. The raised arm 26 now supports the lever 30 of the float cock again, so that the float cock remains closed.

By displacing the pivots 19 and 23 in the slots 18 and 22 respectively the rods 16 and 24 may be adjusted laterally, the pivots 19 and 23 being then locked again to the lever 20.

Owing to the pipe 25 enclosing the pipe 6, splash arising when filling the flushing cistern chamber is prevented from entering the pipe 6 and thus from streaming down on the floor.

As clearly shown in the drawings, the lid, at the beginning of its raising movement, has been disengaged from the lever 13 of the connecting means, but yet the lever 13 has been swung a little distance from the position shown in Fig. 2, due to the weight of the members 16, 20, 24 and 26 constituting the connecting means. As soon as the lid is raised from its lowermost position, said weight is able to swing the lever 13 a little. When the lid is swung downwards after the closet has been used, this movement has no action whatever upon the connecting means (the members 13, 16, 20, 24 and 26) until the lid at the end of its downward movement strikes against the lever 13, and by its weight moves the lever 13 and the members 16, 20, 24 and 26 back to the position shown in Fig. 2.

Flushung devices arranged according to this invention may be made in many other ways than that described as an example, without departing from the spirit and scope of the invention. For instance the seat lid 8 may be connected to the stationary seat member 6 by common hinges, and the angle-lever 13 may be arranged on a special shaft secured to the stationary seat member 6. A chain or rope or the like may be substituted for the rod 16.

Having now described my invention, what I claim as new and desire to secure by Letters Patent is:

1. A water closet comprising a bowl; a water chamber directly located on the closet bowl, said chamber having a supply cock and an outlet valve; a seat and a seat lid; and connecting means between the seat lid on one hand and the supply cock and the outlet valve on the other hand, said connecting means, when the seat lid is in its lowermost position, being actuated by the weight of the lid to open the outlet valve and effect the flushing, the supply cock being held closed and the outlet valve being open as long as the lid remains in the lowermost position, the connecting means between the seat lid and the supply cock being adapted to be released from the lid when the latter is raised from its lowermost position to cut off the supply cock, said connecting means also being adapted to be automatically adjusted, when released from the lid, thereby permitting the supply cock to open automatically without being actuated either by the lid or by the seat.

2. A water closet as claimed in claim 1, in which the adjustment of the connecting means, when released from the seat lid, is effected exclusively by the weight of the members constituting the connecting means.

3. A water closet as claimed in claim 1, in which the connecting means is provided with a float lever supporting member participating in the movement of the connecting means, said float lever supporting member also controlling the outlet valve and being adapted in its highest position, when the lid has been laid down, to support the float carrying lever of a float valve constituting the supply cock, so that the cock is held closed, and at the same time to hold the outlet valve open, said float lever supporting member also being adapted in its lowermost position, when the lid has been raised, to allow the outlet valve to be closed and the float cock to be opened by the action of the weight of the float.

4. A water closet as claimed in claim 1, in which the seat lid is adapted to actuate the connecting means by an angle lever pivoted to the hinge shaft of the seat lid, one arm of said lever being adapted to be actuated by the seat lid when the latter has been laid down, while the other arm is pivoted to the connecting means.

5. A water closet as claimed in claim 1, in which the connecting means consist of a rod pivoted at its upper end to a lever pivoted to the hinge shaft, the lower end of said rod being pivoted to an arm which is pivoted to the closet bowl.

OLOF LUNDBERG.
